CARL SCHRAMM, OF SOUTH COVENTRY, CONNECTICUT, ASSIGNOR TO THE SMYTH MANUFACTURING COMPANY, OF HARTFORD, CONNECTICUT, A CORPORATION OF CONNECTICUT

THROAT PLATE FOR BOOK STITCHING MACHINES

Application filed July 28, 1932. Serial No. 625,352.

This invention relates to machines for stitching together the signatures of books, and more especially to the throat plates of stitching machines of the straight-needle type. In these machines the signatures are carried automatically to the needles, loopers, hooks and carriers which form the stitches that fasten the folded edges of the signatures together. When all of the signatures of a book are stitched it is necessary to cut the threads in order that the signatures of that book may be separated from the signatures of the following book. This has commonly been done by a cutter in the hands of an operative, mechanisms having also been proposed for cutting the threads automatically. Besides the expense, operatives are liable to cut the threads between the wrong signatures, and with the prior automatic cutters it has been necessary in order to prevent the loosening of the threads and separation of the end signatures to form an extra or locking stitch between the signatures of each book, and this interrupts the regular, continuous feed of the signatures with a corresponding decrease in the output.

The object of the present invention is to provide means which will cause the severance of the threads between the books without interrupting the regular continuous feed of the signatures and without danger of cutting the wrong threads or allowing the end signatures of the book to loosen, thus ensuring a maximum output of properly stitched books.

This object is attained by providing the throat plates through which the needles that form the tail stitches and the hooks which form the chain or head stitches pass while stitching, with members movable transversely of the needle paths, which following the stitching of the last signature of each book are shifted so that the threads of the tail stitches will be looped around portions of the movable members and after several of the following signatures have been stitched will be drawn across knife edges of the movable member and severed. As several following signatures are stitched before the threads of the tail stitches are severed, when the books

are separated the threads are drawn taut without pulling out thus obviating the necessity of forming an extra or locking stitch.

In the accompanying drawing Fig. 1 shows a plan view of a throat plate which embodies the invention.

Fig. 2 shows a view of the under side of this plate.

Fig. 3 shows a transverse section of the supporting bar, throat plate and upper edges of some signatures, illustrating a loop of thread formed over a section of the movable member of the throat plate.

Fig. 4 is a section looking from the front on the plane indicated by the dotted line 4-4 on Fig. 3, with the movable member of the throat plate in normal position, as when making the regular stitch.

Fig. 5 is a front section on the same plane showing the movable throat member shifted sideways so as to cause a thread to be wrapped around a part of it.

Fig. 6 is an enlarged sectional view showing a thread loop wound about the movable throat member.

Fig. 7 is a plan view showing a number of stitched signatures with the movable throat member indicated in several positions and the threads severed between the books, the upper portion of the figure showing the books before being separated, the intermediate section showing a book partly separated and the threads as they are being pulled out, and the lower portion showing a book completely separated and the severed ends of the threads drawn out.

The number of throat plates used in these machines depends upon the sizes of the books to be stitched and the distance apart the lines of stitching are to be spaced. A single throat plate is illustrated herein as embodying the present invention and that shown is comprised of a member 1 which is designed to be secured to a supporting bar 2, and members 3 that are movably located in grooves 4 in the under side of the member 1. The fixed member is preferably fastened in a mortise in the under face of the supporting bar by a screw 5, and the grooves are of such width that the members 3 may be shifted transversely. The

fixed member has openings 6 for the passage of the needle 7 and perforations 8 for the passage of the looper hooks 9, and the movable member has openings 10 for the passage of the needles. The inner edges of the openings 10 in the movable members are ground down to form knife edges 11.

- The movable members of the throat plate are fastened to a shifting bar 12 by screws 13.
- 10 The bar 12 is movable lengthwise in a groove in the under side of the supporting bar and is retained in the groove by the fixed member of the throat plates. Filling blocks 14 are placed between the bar and the movable members, these blocks being movable in and guided by slots 15 in the fixed throat member as the movable throat members are shifted. Any suitable connection may be made between the shifting bar and operating mechanism of the machine for reciprocating the bar and shifting the movable members with relation to the fixed members at the desired times.

The needles and the hooks reciprocate as usual always in the same paths. As the signatures are being stitched the needles which form the straight-line or tail stitches pass through the needle openings in the fixed members of the throat plates and also through one of the openings in the movable plates, while the hooks which form the chain or head stitches pass through hook perforations in the fixed members only. On the start the movable members are in such position that the needles draw the threads through the openings 17 in the movable members. After the last signature of a book is stitched the connecting bar is moved so as to shift the movable members sidewise and then while the needles pass through the same opening in the fixed member they pass through the openings 18 in the movable members. This causes loops of the thread to be wound around the sections 19 that are between the openings through the movable members, as shown at the top of Fig. 7. After the last signature of each book is stitched the movable members are shifted so as to loop the tail stitch threads, that is, the movable members are moved to one side and then back to the other side, as indicated in Fig. 7. The stitching continues and after several signatures have been stitched the backward movement of the stitched signatures causes the threaded loops to be drawn across the knife edges of the openings through the movable members and be severed. This is effected at such times that the threads are cut between the last signature of one book and the first signature of the following book, but not until several following signatures have been stitched, so that the drawing of the threads does not loosen the stitching, in fact, it tightens the stitching.

When a book is separated the ends 21, Fig. 7, of the cut tail stitch threads are drawn from the tail stitching through the loops 22

of the chain stitching on the finished book, and then through the loops 23 of the chain stitching on the first signature of the following book. After one book is stitched and before the threads are cut several signatures of the following book have been stitched so that in drawing out the threads the long ends of the threads remain in the loops of the chain and the books can be separated without loosening the stitching.

By the addition of the movable member to the commonly used fixed throat plate the tail stitches are surely looped after the last signature of each book is stitched, and are severed without loosening the stitches, and this is accomplished without interfering with the regular stitching or continuous feed of the signatures.

The invention claimed is:

1. In a machine for stitching the folded edges of book signatures which has a throat plate with an opening for the passage of a needle and an opening for the passage of a hook, a needle that reciprocates vertically through the said needle opening, a hook that reciprocates vertically through the hook opening and a horizontally movable carrier adapted to carry a thread loop from the needle to the hook below the throat plate, a member attached to the throat plate and having a section that moves at intervals transversely across the needle path in a plane parallel with the line between the needle opening and hook opening and dwells on one side of the needle path when the signatures of one book are being stitched and then moves over and dwells on the other side of the needle path when the following book signatures are being stitched, whereby at the finish of the stitching of the signatures of each book the needle thread will be looped over said section and after the feed of several following signatures will be drawn around said section to tighten the stitch and be severed.

2. In a machine for stitching the folded edges of book signatures which has a throat plate with an opening for the passage of a needle and an opening for the passage of a hook, a needle that reciprocates vertically through the said needle opening, a hook that reciprocates vertically through the hook opening, and a horizontally movable carrier adapted to carry a thread loop from the needle to the hook below the throat plate, a blade movable at intervals below the throat plate transversely across the needle path in a plane parallel with the line between the needle opening and hook opening and adapted to dwell on one side of the needle path when the signatures of one book are being stitched and to move over and dwell on the other side of the needle path when the following book signatures are being stitched, whereby at the finish of the stitching of the signatures of each book the needle thread will be looped

over said blade and after the feed of several following signatures will be drawn around said blade to tighten the stitch and be severed.

- 5 3. In a machine for stitching the folded edges of book signatures which has a throat plate with an opening for the passage of a needle and an opening for the passage of a hook, a needle that reciprocates vertically through the needle opening, a hook that reciprocates vertically through the hook opening and a horizontally movable carrier adapted to carry a thread loop from the needle to the hook below the throat plate, a member movable back and forth at intervals below the throat plate in a plane parallel with the line between the needle opening and hook opening, said member having an opening which registers with the needle opening in the throat plate when the signatures of one book are being stitched and an opening with sharpened edges which registers with the needle opening in the throat plate when the following book signatures are being stitched.
- 10 4. In a machine for stitching the folded edges of book signatures which has a throat plate with an opening for the passage of a needle and an opening for the passage of a book, a needle that reciprocates vertically through the needle opening, a hook that reciprocates vertically through the hook opening and a horizontally movable carrier adapted to carry a thread loop from the needle to the hook below the throat plate, a member movable back and forth at intervals below the throat plate in a plane parallel with the line between the needle opening and hook opening, said member having an opening which registers with the needle opening in the throat plate when in one position and the signatures of one book are being stitched and an opening which registers with the needle opening in the throat plate when in its other position and the following book signatures are being stitched, whereby at the finish of the stitching of the signatures of each book the needle thread will be looped from one opening to the other opening of said member and after the feed of several following signatures will be drawn over the section between said opening to tighten the stitch and be severed.

- 15 5. In a machine for stitching the folded edges of book signatures which has a throat plate with an opening for the passage of a needle and an opening for the passage of a hook, a needle that reciprocates vertically through the said needle opening, a hook that reciprocates vertically through the hook opening and a horizontally movable carrier adapted to carry a thread loop from the needle to the hook below the throat plate, a cutter movable back and forth at intervals below the throat plate, transversely across the needle path in a plane parallel with the line between the needle opening and hook opening and adapted to dwell on one side of the needle path when the signatures of one book are being stitched and to move over and dwell on the other side of the needle path when the following book signatures are being stitched.

- 20 6. In a machine for stitching the folded edges of book signatures which has a throat plate with an opening for the passage of a needle and an opening for the passage of a

hook, a needle that reciprocates vertically through the said needle opening, a hook that reciprocates vertically through the hook opening and a horizontally movable carrier adapted to carry a thread loop from the needle to the hook below the throat plate, a member movable at intervals back and forth below the throat plate transversely across the needle path in a plane parallel with the line between the needle opening and hook opening said member having an opening with sharpened edges which registers with the needle opening in the throat plate when the signatures of one book are being stitched and an opening with sharpened edges which registers with the needle opening in the throat plate when the following book signatures are being stitched.

25 7. In a machine for stitching the folded edges of book signatures which has a throat plate with an opening for the passage of a needle and an opening for the passage of a book, a needle that reciprocates vertically through the needle opening, a hook that reciprocates vertically through the hook opening and a horizontally movable carrier adapted to carry a thread loop from the needle to the hook below the throat plate, a flat blade with sharpened rear edges attached to the under side of the throat plate and movable sidewise at intervals transversely across the needle path in a plane parallel with the line between the needle opening and hook opening and adapted to dwell on one side of the needle path when the signatures of one book are being stitched and dwell on the other side of the needle path when the following book signatures are being stitched.

30 8. In a machine for stitching the folded edges of book signatures which has a throat plate with an opening for the passage of a needle and an opening for the passage of a hook, a needle that reciprocates vertically through the needle opening, a hook that reciprocates vertically through the hook opening and a horizontally movable carrier adapted to carry a thread loop from the needle to the hook below the throat plate, a member supported by and movable at intervals back and forth below the throat plate, transversely across the needle path in a plane parallel with the line between the needle opening and hook opening, said member having two openings that alternately register with the needle opening in the throat plate.
